UNITED STATES PATENT OFFICE.

THOMAS C. JOHNSON, OF NEW HAVEN, CONNECTICUT, ASSIGNOR TO WINCHESTER REPEATING ARMS CO., OF NEW HAVEN, CONNECTICUT, A CORPORATION.

MUSHROOM-BULLET.

1,084,342.

Specification of Letters Patent. Patented Jan. 13, 1914.

Application filed September 8, 1913. Serial No. 788,648.

To all whom it may concern:

Be it known that I, THOMAS C. JOHNSON, a citizen of the United States, residing at New Haven, in the county of New Haven and State of Connecticut, have invented a new and useful Improvement in Mushroom-Bullets; and I do hereby declare the following, when taken in connection with the accompanying drawings and the characters of

10 reference marked thereon, to be a full, clear, and exact description of the same, and which said drawings constitute part of this application, and represent, in—

Figure 1 a view in side elevation of a bullet constructed in accordance with my invention, a portion of the jacket body and jacket tip being broken away. Fig. 2 a corresponding view of one of the modified forms which my invention may assume.

20 My invention relates to an improvement in that class of mushroom bullets having two-part jackets circumferentially divided toward the point of the bullet to permit the bullet to more readily mushroom, the 25 object being to produce a bullet of the character described constructed with particular reference to using the jacket-tip to spread and tear open the jacket-body at the time of impact.

30 With these ends in view, my invention consists in a mushroom bullet having certain details of construction as will be hereinafter described and pointed out in the claims.

35 In carrying out my invention, I employ a jacket-body 2 and a jacket-tip 3 made independent of each other and simultaneously swaged in dies upon a "slug" of soft metal. The jacket-tip 3 is slightly reduced at its

40 open inner end to form a circumferential spreading flange 5 which fits snugly within the open end of the jacket-body 2. For the retention of the jacket-tip 3 upon the soft metal core, I provide it, as shown, with a

45 circumferential band of retaining openings 6 placed end to end and located toward the open inner end of the tip 3. These openings 6 have portions of the core exuded into them to form jacket-tip 10 lugs which prevent the 50 tip 3 from longitudinal displacement or rotary movement, and also so weaken the inner end of the tip as to facilitate its breaking down at the time of impact. When the bullet is fired, the effect of the flange 5 of

the tip 3 is to spread open the jacket 2 and 55 thus effect a free mushrooming of the bullet.

In the modified construction shown by Fig. 2, the jacket 8 and tip 9 are constructed in the same manner and operate on the same principle, but the jacket is provided instead 60 of with rectangular openings 6, with openings 10 in the form of the letter W placed end to end.

The construction of Fig. 2 simply illustrates that the openings into which portions 65 of the core are exuded for locking the tip in place, may take an infinite variety of forms, but in any construction the inner edge of the tip will be formed with the spreading flange 5 inserted within the edge of the 70 jacket so that when the tip is crowded longitudinally inward with respect to the jacket the flange 5 will split the jacket-body 8 open and so insure the free breaking down of the forward end of the bullet.

75 It is to be noted that in my improved bullet, the circumferential line 11 on which the two parts of the jacket are joined will be hardly noticeable and that the joint exposes no portion whatever of the core.

80 I claim:—

1. As a new article of manufacture, a full-jacketed, sharp-nosed mushroom bullet, cylindrical at its rear end and pointed at its forward end, the said bullet having a soft-metal core, a jacket-body swaged thereupon and extending forward toward the point thereof, its forward edge being straight, and a jacket-tip swaged upon the point of the core and having its open inner end, 85 which is smaller in diameter than the full diameter of the bullet, formed with an annular spreading-flange inserted within the straight forward edge of the jacket-body in line with the said edge thereof and extending rearward beyond the said edge in contact with the inner face thereof for spreading the jacket-body open at the time of the impact of the bullet.

90 2. As a new article of manufacture, a full-jacketed, sharp-nosed, mushroom bullet having a cylindrical rear portion and tapering forward therefrom to a point, the said bullet comprising a soft-metal core, a jacket-body swaged thereupon and extending 95 forward toward the point thereof, and a jacket-tip applied to the point of the core, having its inner end made smaller in di-

ameter than the cylindrical portion of the bullet, formed with a spreading-flange adapted to be inserted within the outer end of the jacket-body in line with the edge thereof, for spreading the same open when the jacket-tip is driven into the jacket-body by the impact of the bullet, and the said tip being formed with one or more retaining-openings into which the metal of the

core is exuded for securing the tip in place 10 upon the core.

In testimony whereof, I have signed this specification in the presence of two subscribing witnesses.

THOMAS C. JOHNSON.
